SPINDLE MOUNTING FOR TEXTILE SPINNING OR LIKE MACHINES

Arthur Westall, Accrington, England, assignor to
 T. M. M. (Research) Limited, Rossendale,
 England

Application June 21, 1951, Serial No. 232,817
 Claims priority, application Great Britain
 May 25, 1950

4 Claims. (Cl. 57—135)

1

This invention is concerned with the mounting of spindles of textile spinning, doubling and twisting machines, such spindle mounting being of the type wherein the spindle bolster is resiliently borne in the spindle rail, carrier bracket or the like, so as to be capable of a controlled oscillatory or gyratory movement in relation thereto. Examples of such known type of spindle mounting are disclosed by British Patent Specification No. 329,485 and United States patent specification No. 2,486,730, in which springs are compressed both above and below a spindle rail, respectively between the upper side of said rail and a shoulder on the bolster, and between the underside of said rail and a nut screwing upon the part of the bolster which protrudes downwardly through the spindle rail.

This invention has for its object to provide an improved form of spindle mounting of the aforesaid type, which will enable a spindle to be driven at speeds higher than is customary without developing undue vibration due to the dynamic unbalance of the yarn package or to faulty design or manufacture of the spindle itself. For this purpose a spindle is supported in the spindle rail, carrier bracket or the like by two opposed springs one of which is compressed between the underside of said rail, bracket or the like and an adjustable abutment on the downwardly protruding part of the spindle bolster, whilst the other spring is compressed between a shoulder or other fixed abutment on the upper part of the bolster and a collar which is slidable on the bolster and is arranged to transmit the force of said upper spring equally to a resilient annular packing housed in the spindle rail, carrier bracket or the like and a second adjustable abutment on the bolster.

Said second-mentioned abutment on the bolster may be constituted by a nut screwed thereon, and in a modification a third spring may be introduced between the opposed faces of said collar and said abutment.

Two embodiments of the invention are hereinafter described with reference to the accompanying drawings, in which Fig. 1 is a vertical section of a spindle assembly for that kind of textile spinning machine which is known as an "uptwister." Fig. 2 is a similar view to Fig. 1 of a modification.

In Fig. 1 the reference numeral 10 indicates the spindle-supporting member which is mounted pivotally by means of a pin 11 in the bracket 12, which latter is adapted to be fixed to the machine framing in conventional manner. Said

member 10 is apertured at 13 to receive the bolster 14 of the spindle assembly. (Said assembly includes an inner bearing tube 15 supporting the spindle blade 16 by a journal bearing 17 and a footstep bearing 18, and a combined wharve and bobbin support 19 which is carried on the blade 16 so that the wharve coincides substantially with the bearing 17.)

The spindle assembly is supported upon the member 10 by means of two opposed springs 20, 21 which are arranged co-axially with the bolster, respectively embracing the latter above and below the member 10. The spring 20 is compressed between a shoulder 22 on the upper part of the bolster 14 and a collar 23 which is free to slide on the bolster and the underside of which is of sufficient breadth to enable it to bear downwardly equally upon a resilient packing ring 24 which is located in a recess in the upper side of the member 10, and a nut 25 which is threaded on the bolster. A locknut 26 is provided for securing the nut 25 in position. The spring 21 is compressed between the underside of the member 10 and a nut 27 threaded on the shank of the bolster 14. 28 is a locknut for said nut 27.

The aperture 13 in the member 10 is of sufficient diameter to provide ample clearance within it for the nuts 25 and 26, and the arrangement is such that when the spindle is stationary the assembly will take up a central position in said aperture 13.

In an alternative embodiment (not shown) the spring 21 may seat at its upper end against a resilient packing ring located in a recess in the underside of the member 10. A collar such as that indicated at 23 may also be interposed between the spring and the packing ring.

In the modified embodiment shown in Fig. 2, additional flexibility is achieved by introducing a third spring 30 between the under-face of the collar 23 and the nut 25.

The position of the bolster when the spindle is stationary depends upon the relative stiffness and the relative compression of the springs 20, 21, which latter condition may be varied by adjusting the settings of the nuts 25 and 27 on the bolster. If desired one spring may be subjected to a greater degree of compression than the other.

The arrangement in both the aforescribed embodiments of the invention is such that both radial and axial movements of the spindle assembly are accommodated by the flexibility of the opposed springs. The opposed arrangement of the springs is effective to absorb vibrations

which would otherwise be transmitted from the spindle through the bolster to the supporting member 10.

What I claim as my invention and desire to secure by Letters Patent is:

1. A spindle mounting comprising, in combination, a carrier having an opening therein, a spindle supporting bolster disposed to extend substantially vertically through said opening and out of contact with said carrier, and means for resiliently supporting the bolster from the carrier comprising an abutment adjustably secured on a downwardly protruding portion of the bolster, a first spring compressed between the underside of the carrier and said abutment, a 15 fixed abutment on the upper part of the bolster above the carrier, a collar surrounding the bolster and movable longitudinally thereof, a resilient angular packing supported in the carrier and having an upper face exposed to the collar, a 20 second adjustable abutment on the bolster, and a second compressed spring opposed to the first and bearing at its upper end against the fixed abutment on the bolster and at its lower end upon said collar, the collar being disposed to 25 bear both upon the annular packing and upon the second adjustable abutment on the bolster.

2. A spindle mounting as claimed in claim 1, comprising a third spring introduced between

said collar and the abutment against which said collar is arranged to bear.

3. A spindle mounting as claimed in claim 1 wherein at least one of the adjustable abutments is constituted by a nut threaded on the bolster, and comprising means for locking said nut in any desired setting.

4. A spindle mounting as claimed in claim 1, wherein a third spring is included between the collar and the second adjustable abutment, the springs being of different stiffness, and the adjustable abutments serving through their adjustments to vary the compression of the springs relative to one another.

ARTHUR WESTALL.
